US0D1040669S

(12) **United States Design Patent** (10) Patent No.: **US D1,040,669 S**
(45) Date of Patent: ** Sep. 3, 2024

- (54) **CASE FOR DYNAMIC SENSOR FOR RUNNING**
(71) Applicant: **BEIJING XIAOMI MOBILE SOFTWARE CO., LTD.**, Beijing (CN)
(72) Inventors: **Huacan Cui**, Beijing (CN); **Jiasheng Huang**, Beijing (CN)
(73) Assignee: **BEIJING XIAOMI MOBILE SOFTWARE CO., LTD.**, Beijing (CN)
(**) Term: **15 Years**
(21) Appl. No.: **35/518,875**
(22) Filed: **Oct. 11, 2023**
(80) **Hague Agreement Data**

Int. Filing Date: **Oct. 11, 2023**Int. Reg. No.: **DM/232559**Int. Reg. Date: **Oct. 11, 2023**Int. Reg. Pub. Date: **Nov. 3, 2023**

(57) **CLAIM**

The ornamental design for a case for dynamic sensor for running, as shown and described.

DESCRIPTION

2. Case for dynamic sensor for running

2.1 : Front

2.2 : Back

2.3 : Left

2.4 : Right

2.5 : Top

2.6 : Bottom

2.7 : Perspective

2.8 : Perspective
